United States Patent Office

Des. 179,365
Patented Dec. 4, 1956

179,365

TELEPHONE DIALER OR THE LIKE

Cecil B. Woofter, Minneapolis, Minn., assignor to U. O.
Colson Company, Paris, Ill., a corporation of Delaware

Application May 17, 1956, Serial No. 41,526

Term of patent 14 years

(Cl. D26—14)

Fig. 1 is a perspective view of a telephone dialer or the like showing my new design;

Fig. 2 is a left end elevational view thereof;

Fig. 3 is a front elevational view thereof;

Fig. 4 is a rear elevational view thereof;

Fig. 5 is a top plan view thereof;

Fig. 6 is a bottom plan view thereof; and

Fig. 7 is a right end elevational view thereof.

I claim:

The ornamental design for a telephone dialer or the like, as shown.
